HERMAN H. TOLL, OF CLARINDA, IOWA, ASSIGNOR TO CLARINDA LAWN MOWER COMPANY, OF CLARINDA, IOWA, A CORPORATION OF IOWA.

WRINGER DRIVING MECHANISM.

1,325,884.

Specification of Letters Patent.

Patented Dec. 23, 1919.

Application filed November 26, 1917. Serial No. 204,073.

To all whom it may concern:

Be it known that I, HERMAN H. TOLL, citizen of the United States of America, and resident of Clarinda, Page county, Iowa, 5 have invented a new and useful Wringer Driving Mechanism, of which the following is a specification.

The object of this invention is to provide improved means for operating a wringer 10 mechanism from a source of power.

A further object of this invention is to provide a simple and compact driving mechanism for operating a wringer mechanism in either direction from a source of power.

15 A further object of this invention is to facilitate the control of a wringer mechanism, as to operation in either direction or cessation of movement.

A further object of this invention is to 20 provide improved means for mounting a wringer mechanism on a support for oscillation through an arc on a vertical axis.

A further object of this invention is to 25 provide improved means for mounting a wringer mechanism on a support for oscillation through an arc on a vertical axis, and for operating said mechanism in either direction irrespective of its position relative to the support.

30 My invention consists in the construction, arrangement and combination of elements hereinafter set forth, pointed out in my claims and illustrated by the accompanying drawing, in which—

35 Figure 1 is a side elevation showing my improved wringer mechanism mounted on a support, a portion only of which is shown. Fig. 2 is an elevation at right angles to Fig. 1. Fig. 3 is a vertical section, on an enlarged scale, on the line 3—3 of Fig. 2. Fig. 4 is a vertical section on the line 4—4 of Fig. 3. Fig. 5 is a detail sectional elevation on an enlarged scale on the line 5—5 of Fig. 2.

40 In the construction of the device as shown the numeral 10 designates a support such as a washing machine tub, which may be of any desired form and construction. The tub 10 is provided with a fixed cover member 11 and a movable cover member 12 hinged thereto in any desired manner. A supporting plate 13 is mounted on and fixed to the fixed cover member 11, and a driving shaft 14 is journaled for rotation in bearings carried by said plate, and is adapted

to be operated by any suitable means. The driving shaft 14 preferably is inclosed by a sleeve 15 in part.

At one end the supporting plate 13 is offset upwardly and a cylindrical gear casing 60 16 is formed integrally thereon, said casing having its axis arranged vertically, and projecting beyond the tub. A bearing member 17 also is formed integrally on the supporting plate 13 and projects beneath, spaced 65 from and arranged coaxially with the gear casing 16. A supporting arm 18 is provided and carries a wringer mechanism, indicated generally by the numeral 19, which may be of any desired type and construction, 70 said wringer mechanism having one of its wringer roll shafts projected materially beyond the frame and indicated by the numeral 20.

A sleeve 21 is fixed rigidly through the 75 bottom of the gear casing 16 and projects upwardly part way within said casing and also projects downwardly through the bearing 17 and beyond said bearing. The wringer supporting arm 18 is forked at one 80 end and formed with spaced bearings 22, 23, pivoted on the sleeve or spindle 21 above and below the bearing member 17 respectively. A bottom plate 24 is fixed to the lower end of the sleeve or spindle 21 beneath the bearing 23, and may be secured to the bearing member 17 by a bolt 25. Thus, the wringer is mounted for oscillation on a vertical axis by articulation of the bearings 22, 23 on the hollow spindle or sleeve 21. 85

The driving shaft 14 projects at one end through the gear casing 16 and a bevel gear 26 is fixed to said shaft within the casing. A countershaft 27 is arranged vertically in and axially of the gear casing 16 and has 95 its lower end journaled in the upper portion of the sleeve 21 and its upper end journaled in and projecting through the removable top 28 of said casing. A bevel gear 29 is fixed to the countershaft 27 within the 100 casing 16 and meshes with and is adapted to be driven by the bevel pinion 26. A second gear casing 30 is mounted above the casing 16 and the extended wringer roll shaft 20 projects within said casing 30. The casing 30 is formed with opposed bearings 31, 32 axially of the shaft 20, and opposed bevel gears 33, 34 are mounted in said casing, loosely on said shaft 20, and have their hubs journaled in said bearings 31, 32. A bevel 105 110

gear 35 is fixed to the projecting upper end of the countershaft 27, within the upper casing 30, and meshes with and is adapted to drive continuously the bevel gears 33, 34, 5 in opposite directions. The bevel gears 33, 34 are formed with opposed clutch faces 36, 37, and a clutch member 38 is mounted between said gears, is feathered for sliding movement on the shaft 20, and is adapted 10 to be engaged selectively with the clutch faces 36, 37 of said gears, or to be located in neutral position between said clutch faces and out of contact with either, as shown in Fig. 3. The clutch member 38 is formed 15 with a peripheral groove 39. A rocker shaft 40 is journaled in horizontal position in the gear casing 30 and is formed with spaced, downwardly projecting lugs 41, 42 engaging loosely within the groove 39 of the clutch 20 member 38. A crank handle 43 is formed on a projecting end portion of the rocker shaft 40, and preferably terminates in a laterally extended knob 44 adapted to be grasped manually to actuate said shaft. A 25 vertical slide bearing 45 is formed on the crank handle 43, and a spring-actuated plunger pin 46 is slidably mounted in said bearing and is adapted to engage selectively at its projecting lower end one or another 30 of spaced contact points 47, 48, 49 formed on the top of the casing 30, and designed to yieldingly hold the rocker shaft 40 in any position in which it may be placed manually. When the plunger pin 46 is in contact 35 with the central contact point 48 the crank handle 43 is in upright or neutral position and the clutch member 38 is in intermediate or neutral position out of contact with both clutch faces 36, 37; and said crank handle 40 may be moved laterally in either direction, through an arc, to cause the clutch member 38 to engage either of the clutch faces 36 or 37 to drive the wringer roll-shaft 20 in either direction as desired, the plunger pin 45 46 contacting with either contact point 47 or 49 to hold it in such position.

Thus provision is made for operating the wringer mechanism either forwardly or reversely from the driving shaft, and for 50 readily controlling the direction of operation or the cessation thereof. Such operation and control may be exercised at will independently of the position of the wringer mechanism relative to its axis of oscillation 55 on the support, which position may be varied to enable the operator to employ the wringer relative to the tub 10 or to other extraneous containers located adjacent thereto. When it is desired to shift the position 60 of the wringer mechanism it is moved manually through an arc, the bearings 22, 23 of the supporting arm 18 rotating on the fixed spindle 21, the driving members maintaining their respective relations. It will be observed that the rotary oscillation of the 65

wringer mechanism and its support, as well as the method of mounting said support (the arm 18) from the support 10 and members carried thereby, is entirely independent of and disconnected from the vertical countershaft 27, thereby avoiding undue strain on and danger of displacement of said shaft. The supporting arm 18 has its bearings on the fixed spindle 21 and turns about said spindle in a plane below the position of the 75 countershaft 27.

Any desired means may be employed for fixing and temporarily maintaining the wringer and its support 18 in its position of arcuate adjustment. To this end a rod 80 50 is mounted for rectilinear reciprocation in bearings 51 carried by and depending from the supporting arm 18, and is adapted to engage selectively at one end in one of a plurality of notches or seats 52, of any desired number, formed in and circumferentially of the gear casing 16. A light spring 53 preferably is coiled around the rod 50 and engages a bearing 51 and a collar 54 fixed to said rod, to yieldingly hold said rod 90 to its selected seat. A lever 55 is pivoted to one end of the rod 50, beyond the outermost bearing 51, and is formed with two flat faces at right angles to each other and at unequal distances from the pivot, adapted 95 to engage selectively with the face of the said bearing. When the lever 55 is extended and has its end face in contact with the bearing 51, the rod 50 is withdrawn, against the influence of the spring 53, so that the 100 wringer support and wringer may be moved through an arc; and when the lever is turned at right angles to the rod, as shown in Fig. 1, and has its lateral face engaging the bearing 51, the rod 50 is seated in one or another of the notches, under the influence of the spring 53, or is free to become seated when in registry with either of said notches. 105

The spring 56 in the slide bearing 45 may be retained by a pin 57 passed through said bearing above said spring, which engages at its lower end the plunger pin 46.

I claim as my invention—

1. A device of the class described, comprising a support, a supporting plate fixed 115 thereto, a driving shaft journaled on said supporting plate, a gear casing rigidly carried by said supporting plate, within which gear casing said driving shaft extends, a hollow spindle mounted axially within and 120 projecting beneath said gear casing, a wringer mechanism pivoted on the projecting portion of said spindle, a countershaft vertically arranged, journaled in the upper portion of said hollow spindle, and projecting through the top of said casing, driving connections within the casing between the driving shaft and countershaft, a second gear casing pivoted on the projecting portion of the countershaft, said wringer mech- 125 130

anism including a shaft extending within the second gear casing, and clutch-controlled driving connections between said countershaft and wringer shaft.

5 2. A device of the class described, comprising a support, a supporting plate fixed thereto, a horizontally arranged driving shaft journaled on said supporting plate, a gear casing rigidly carried by said support-

10 ing plate, within which gear casing said driving shaft extends, a hollow spindle mounted within and projecting beneath said gear casing, a wringer mechanism pivoted on the projecting portion of said spindle, a

15 countershaft vertically arranged, journaled in the upper portion of said hollow spindle and projecting through the top of said casing, a bevel gear fixed to the countershaft within the casing, a bevel gear fixed to the

20 driving shaft and meshing with the first-mentioned bevel gear, a second gear casing pivoted on the projecting portion of the countershaft, said wringer mechanism including a shaft extending within the second

25 gear casing, and clutch-controlled driving connections between said countershaft and wringer shaft within the second gear casing.

3. A device of the class described, comprising a support, a supporting plate thereon, a driving shaft journaled on said supporting plate, vertically spaced bearing members formed on said supporting plate, a wringer mechanism, a supporting arm on

35 which said mechanism is carried, said arm being bifurcated at one end and formed with spaced bearings, a fixed spindle carried by the spaced bearings of said supporting plate and providing journals for the bearings of said supporting arm, a countershaft ver-

40 tically arranged and stepped in the upper bearing of said supporting plate, driving connections between said driving shaft and countershaft, and clutch-controlled driving connections between said countershaft and

45 the wringer mechanism.

4. A device of the class described, comprising a support, a supporting plate thereon, a driving shaft journaled on said supporting plate, said supporting plate being

50 formed with a gear casing and a bearing member spaced therebeneath, a fixed spindle carried by said casing and bearing member, a wringer mechanism, a supporting arm carrying said wringer mechanism and

formed at one end with spaced bearings 55 journaled on said spindle on opposite sides of said bearing member, a countershaft vertically arranged and stepped for rotation in said gear casing, driving connections between said driving shaft and countershaft, 60 and clutch-controlled driving connections between said countershaft and the wringer mechanism.

5. A device of the class described, comprising a support, a driving shaft journaled 65 thereon, a wringer mechanism on said support having a shaft, a countershaft vertically arranged and adapted to be operated from said driving shaft, a bevel gear fixed to the upper end of said countershaft, a gear 70 casing inclosing said bevel gear, into which casing the shaft of said wringer mechanism is extended, opposing bevel gears loosely mounted on said wringer shaft in mesh with the first mentioned bevel gear, said opposing 75 bevel gears being formed with opposed clutch faces, a clutch member feathered on said wringer shaft and adapted to engage selectively said clutch faces, a rock shaft journaled in said casing and formed with 80 means for loosely engaging and sliding said clutch member, a crank handle on said rock shaft outside of said casing, and a spring-actuated latching member carried by said crank handle, said casing being formed with 85 spaced means for engagement by said latching member.

6. In a mechanism of the class described, a casing and a shiftable member in said casing, said shiftable member being formed 90 with a circumferential groove, in combination with a rock shaft journaled in said casing at one side of, extending across and substantially at right angles to the axis of said shiftable member, said shaft being formed 95 with a fork engaging the groove of said shiftable member, said shaft being formed with a crank handle, a slide bearing on said crank handle, and a spring-pressed plunger contained substantially within and projecting at one end only from said slide bearing, said casing being formed with a plurality of contact faces at varying angles adapted to be engaged selectively by the projecting end of said plunger. 100

Signed by me at Clarinda, Iowa, this 18th day of July, 1917. 105
